[57] CLAIM

The ornamental design for an automatic dialing apparatus for telephone, as shown and described.

DESCRIPTION

FIG. 1 is a top front perspective view of an automatic dialing apparatus for a telephone showing my new design;

FIG. 2 is a top plan view thereof;

FIG. 3 is a bottom plan view thereof;

FIG. 4 is a front elevation thereof;

FIG. 5 is a left side elevation thereof;

FIG. 6 is a rear elevation thereof;

FIG. 7 is a top plan view similar to FIG. 2, but in a display mode;

FIG. 8 is a top front perspective view, the broken lines representing the telephone are shown for illustrative purposes only.

FIG. 9 is a top front perspective view of a modified embodiment of the dialing apparatus illustrated in FIG. 1;

FIG. 10 is a top plan view thereof;

FIG. 11 is a bottom plan view thereof;

FIG. 12 is a front elevation thereof;

FIG. 13 is a left side elevation thereof;

FIG. 14 is a rear elevation thereof;

FIG. 15 is a top plan view similar to FIG. 2, but in a display mode; and

FIG. 16 is a top front perspective view, the broken lines representing the telephone are shown for illustrative purposes only.
